TO THE ANTHONY COMPANY, OF STREATOR, ILLINOIS, A CORPORATION OF
ILLINOIS

HYDRAULIC HOIST DUMPING BODY

Application filed November 19, 1930. Serial No. 496,632.

This invention relates to a dumping body and to means for moving it to dump it.

One object is to provide a hydraulic dumping body and a mechanism for dumping it.

Another object is to provide a hydraulic operating mechanism by means of which the body may be dumped. Another object is to provide a hydraulic dumping assembly, in which the actuating parts may be driven in either direction by the substitution of a single member.

Other objects will appear from time to time in the specification and claims.

My invention is illustrated more or less diagrammatically in the accompanying drawings, wherein—

Figure 1 is a side elevation showing the body in position on a truck, with the dumping position indicated in dotted lines;

Figure 2 is a plan view of the vehicle frame, with the body and a portion of the dumping mechanism removed;

Figure 3 is an end elevation with parts broken away and parts in section, showing the pumping mechanism;

Figure 4 is a vertical cross section, taken at line 4—4 of Figure 3;

Figure 5 is a side elevation of the truck, and body tipping mechanism, with the body removed, showing a modified form of controlling and stopping mechanism, with parts in section.

Figure 6 is a similar view, showing a further modified form of the controlling and stopping mechanism.

Like parts are designated by like characters throughout the specification and drawings.

A, A are automobile frame members. A¹ is a seat. A² are wheels. A³ is an axle. A⁴ are springs. A⁵, A⁵ are cross frame members. A⁶, A⁶ are angles preferably supported on the cross frame members. A⁷, A⁷ are pivots on the rear cross frame member A⁵, upon which a body A⁸ is pivotally mounted.

B is a body raising lever preferably comprising two side members, as indicated in Figure 2. It is mounted on a shaft B¹ which is supported on the angles A⁶. At its upper or free end each side member of the lever B¹ carries a roller B² which contacts the bottom of the body A⁸ and may run in a track provided on the bottom of the body.

C is a cross head provided with pairs of wheels C¹ adapted to run on track members C² which are supported on the angles A⁶. The cross head C also has a pair of wheels C³ adapted to contact the under side of the side members of the lever B as indicated particularly in Figure 1. The cross head is fastened to a piston rod C⁴ which extends within a hydraulic cylinder D. The details of the piston and the interior of the cylinder will be described below.

The cylinder itself may be supported at one end upon a cross member D¹ which is joined to the angles A⁶ and the cylinder is held against displacement by means of a U-bolt D² which is fastened to the cross member D¹. At its opposite end the cylinder is fastened to a housing D³. A supporting and connecting member D⁴ passes through the housing and its ends rest upon and are preferably engaged in the angles A⁶. The housing D³ is provided with an inlet port D⁵ within which is seated a ball check valve D⁶. It is also provided with a cavity or hollow space D⁷ having a plurality of outlets D⁸ and communicating with the interior of the cylinder D. D⁹ is a ball check valve controlling discharge from the cylinder D to the cavity D⁷. The valve D⁹ is normally held seated by the spring shown, or by pressure within the cylinder or by both. A controlling member for unseating the valve D⁹ is provided in the shaft-like part D¹⁰ which has a flattened portion D¹¹ and a controlling lever D¹² extending preferably above the axis of movement of the member D¹⁰. The shaft-like member D¹⁰ may be positioned

- as shown in Figure 4 and in that position its flattened portion is in contact with the ball valve and the latter remains closed. If the shaft is rotated, the ball is forced out of the flattened portion and the valve is opened. At its outer end the cylinder D may be closed by a plate or head D¹³ which may be of any suitable design and in which a stuffing box or other necessary parts may be positioned.
- 5 An adjustable valve opening member D¹⁴ is positioned within the member D¹³. As shown, it comprises a screw, adjustable in and out in the member D¹³, and carries at its inner end a contact head D¹⁵. D¹⁴ is a pipe or 10 passage running preferably from the outer end of the cylinder D to the space D⁷ within the housing D⁸. By means of this passage fluid on the right of the piston, as indicated in Figure 4, may move from that position, back 15 into the main fluid supply chamber or tank.
- The piston may be formed of two members E, E¹ which are preferably metallic and which support and partially enclose a cup-shaped leather or fabric member E². A ball 20 check valve E³ may be positioned in the piston. When pressure is on the left side of the piston, as shown in Figure 4, the valve is held seated. When the piston approaches 25 the outer limit of its movement the member D¹⁵ contacts the ball and unseats the valve.
- Fastened to the housing D⁸ and communicating with it through the passages D⁸ is an 30 oil reservoir F. It has an open top which may be closed by a cover F¹, which is provided with breather openings F². The member F is larger at its top as indicated in Figure 4 and is laterally bent and disposed as indicated in Figure 3. Formed along one side of the member F and preferably integrally 35 with it, is a pressure passage F³ which communicates with the pressure inlet D⁵ in the housing D⁸ and through which oil under pressure is forced to the cylinder to move the piston. In the bottom of the chamber 40 formed within the member F are two openings F⁴, F⁵. These communicate with a pump in the manner which will be described 45 below.
- Joined to the reservoir member F is a 50 pump. A portion of the pump housing may be integral with the reservoir or it may be made separately and attached to it. In the form shown herewith the main portion of the pump housing is shown as being integral with 55 the reservoir member F and it is provided with a separate cover plate which completes the pump housing.
- The pump housing thus is formed of a portion G and a separate cover plate. The housing portion G will be described first. As indicated particularly in Figure 4, a portion 60 of the passage F³, above mentioned, extends into or lies within the housing portion G. G¹ is a duct or passage formed within the housing G and normally placed opposite or

formed opposite the opening F⁴ in the member F. That portion of the passage F³ which lies within the housing member G is joined to two oppositely directed branches G² and G³, each of which has an outlet or inlet opening G⁴, G⁵, respectively. G⁶, G⁷ are cavities formed within the member G and adapted to receive gears G⁸, G⁹ of a gear pump. The gear G⁸ is carried on a stub shaft G¹⁰ and the gear G⁹ is carried on a driven shaft G¹¹.

H is a cover plate which is mounted upon or attached by any suitable means to the pump housing member G. It is provided with a cavity H¹ which serves as a bearing for the stub shaft G¹⁰ and is provided with an opening or perforation H² through which the drive shaft G¹¹ may pass. Any suitable packing arrangement may be provided to prevent leakage.

In Figures 1 and 5 is illustrated a throw-out mechanism. As described, the check valve D⁹ will normally remain in the closed position as shown in Figure 4, unless the shaft D¹⁰ is rotated so as to move the depression or flat portion D¹¹ out of contact with the ball and thus to unseat the ball and to open the valve. As shown in Figure 1, the lever D¹² is provided with a forwardly reaching link I which may be fastened to a hand lever I¹ situated conveniently to be manipulated by the driver. By moving the handle I¹ he may rotate the shaft D¹⁰ and thus open the check valve and stop the raising of the body in any suitable position. The portion D¹³ of the lever D¹² which projects below the axis of rotation of the shaft D¹⁰ might be continuous with the upwardly projecting part or might be set at the opposite end of the shaft as indicated in Figure 12. Fastened to this downwardly projecting portion is a rearwardly projecting link I² which is downwardly bent as at I³ and carries an adjustable contact member I⁴ which will be struck by some part of the cross head or a part carried by the cross head as it approaches or reaches its outer limit, so that the shaft D¹⁰ will be rotated to open the valve and stop the hoisting.

In the form shown in Figure 6, the hand throw-out connection is the same as that shown in the earlier forms. The lower portion D¹³ or downwardly extending portion of the lever D¹² is omitted. The safety or limiting throw-out does not act upon the valve but upon the power take off to stop rotation of the pump and thus to stop further discharge of fluid into the pressure cylinder and accordingly to stop further raising of the body. J is a power take off from which a shaft J¹ leads to the pump. J² is a pivoted lever. At its lower end a link J³ passes through it and is fastened to it with a movable connection which is made possible by the use of the spring J⁴. At its other end the link J³ is fastened to a power take off controlling

lever J^5 . Extending rearwardly from the lever J^2 is a link J^6 having an upwardly bent portion J^7 which carries an adjustable contact member J^8 . This member is positioned 5 to be contacted by some part of the cross head or cross head assembly. When the cross head approaches or reaches the outer limit of its movement, it strikes the contact member J^7 and by means of the linkage 10 shown, the power take off is disconnected and the pump is stopped.

K, K are ears or projections formed on the side of the reservoir F and extending laterally from it. The outer ends of the ears are 15 preferably downwardly bent as indicated in Figure 3. K^1 is a bolt passing between the ears and having its head engaged between them. K^2 is a spring positioned about the upper end of the bolt and bearing at one end 20 upon the horizontal flange of the angle A^6 . K^3 is a nut positioned upon the bolt K^1 . K^4 is a washer positioned between the nut and the spring K^2 .

It will be realized that whereas I have here- 25 with shown and described a practical operative device, nevertheless many changes might be made in the size, shape, number and disposition of parts without departing from the spirit of my invention and I wish, therefore, 30 that my showing be taken as in a sense dia- grammatic.

Particularly the means for automatically 35 limiting the movement of the piston in the raising direction might be changed. Any one of the several means shown might be used and almost any other means might be used. Under some conditions no automatic stop or 40 throw-out would be used and the control would be entirely manual.

The use and operation of my invention are 45 as follows:

If the parts are in the position shown in full line in Figure 1 and it is desired to dump the body, the power take-off control is operated so as to drive the pump and fluid is forced from the pump into the cylinder. The piston is thus moved outwardly or to the right, as indicated in the figures, and the rollers which are carried by the cross head 50 attached to the piston are forced under the lever assembly B , the latter being tilted upwardly. As it moves about its pivot, rollers at its upper end move in contact with the bottom of the body bearing either directly 55 upon it or in channels or tracks, as shown, and the body is correspondingly tilted upwardly, as indicated in dotted lines in Figure 1. When the body has been moved in the tilted direction as far as desired, the 60 movement of the piston is stopped, either by stopping the pump or by operating one of the controls, either automatic or manual, so as to open the relief valve E^3 in the piston or to open the valve D^9 . Ordinarily it is prefer- 65 able to use one of the forms of automatic

throw-out to prevent injury to the parts and to prevent excessive dumping movement.

The throw-out mechanism illustrated in Figures 1 and 4, includes both an automatic and a manual throw-out. As shown in Figure 4 the piston is provided with a ball check valve E^3 and a cylinder head D^{13} is provided with a stop member D^{14}, D^{15} , positioned to contact this valve. As the piston moves outwardly under the influence of pressure on its left side, as shown in Figure 4, it finally comes to a position in which the member D^{15} 70 contacts the ball E^3 , forces it from its seat and thus opens it and permits liquid to discharge through the valve. When this takes place the force moving the piston to the right or in the dumping direction, is not sufficient to continue the movement of the piston and this thus serves as an automatic stop for 75 movement of the piston. In the form shown in Figure 4, there is also provided a manual control. The valve D^9 in the opposite end of the cylinder is ordinarily held closed by the spring shown against it and by pressure 80 within the cylinder. At any time in the cycle of operation this valve may be opened by rotating the shaft D^{10} so as to move the depression D^{11} out of contact or alignment with the ball D^9 . When this takes place, the ball is raised from its seat and liquid may 85 discharge through the valve and thus the pressure forcing the piston to move outwardly in the dumping direction is reduced and outward movement of the piston is stopped.

The parts may be so proportioned that when 90 this valve is opened the weight of the body will move the piston in the reverse or left hand direction and so when this valve is opened the body may be permitted to return 95 to its original position. The parts, however, may be so proportioned that the opening 100 of the valve is not sufficient to permit lowering of the body but is merely sufficient to prevent further raising movement. The manual control of the valve D^9 is, of course, 105 accomplished by means of the hand lever I^1 and the link I acting on the upwardly extending portion of the lever D^{12} .

As shown in Figure 5 this form of automatic throw-out is provided. In this form 110 means are provided for opening the ball check valve D^9 automatically in response to movement of the piston in the outward or dumping direction. The adjustable contact member I^4 will be struck by some part of the outwardly moving cross head. This will 115 rotate the downwardly extending portion of the lever D^{12} and will so move the shaft D^{10} as to unseat the ball D^9 . In this form of 120 the device, the valve in the piston would ordinarily be omitted.

In Figure 6 a further modified form of 125 throw-out device is shown. In the early forms of throw-out the pump may continue 130 constantly in motion and the operation of

the valves alone serves to stop the raising of the body and to permit its return to its original position. In the form shown in Figure 13 the pump is stopped by disconnecting the power take-off mechanism. In the operation of this throw-out an adjustable contact member J^8 is provided and positioned to be struck or contacted by a portion of the cross head assembly. When this takes place the lever J^2 is moved and through it the link J^3 is also moved to operate the lever J^5 and to disconnect the pump driving means for the power take-off. The spring J^4 is provided to cushion the shock of the movement and to permit the play necessary when the parts are again put into driving connection to start the pump.

The entire assembly is designed, of course, to be mounted on a vehicle frame and inevitably when such a vehicle is driven along a road surface some flexing or weaving of the vehicle frame will take place. To compensate for this or to prevent breaking or straining of the parts as a result of it, the pump and assembly are given a three-point suspension. The pump assembly is supported at one end upon the shaft or ball D^4 , which rests at each end in one of the angles A^6 . At its forward end the cylinder is supported on the cross member D^1 to which it is fastened by the U-bolt D^2 . This U-bolt is preferably left slightly loose so as to permit some movement of the cylinder in it. In most automotive vehicles the drive shaft of the vehicle is positioned centrally and to permit this to pass the reservoir F is bent laterally as indicated in Figure 3. To compensate for the unequal distribution of the weight which results from this formation the reservoir is supported on its side. For this purpose the reservoir is provided with the outwardly projecting ears K , K , through which a bolt K^1 passes, the head of the bolt being engaged in the ears. The bolt passes through one of the angles A^6 and has about it and above the angle a compression spring K^2 which is held in adjustable position on the bolt by a nut K^3 and a washer K^4 . The compression of the spring may be adjusted and it and the bolt serve to provide a cushioned support for the reservoir and the pump assembly which is attached to it.

I claim:

1. In combination with an automotive vehicle having a frame, a dumping receptacle pivotally supported therefrom, means for dumping the receptacle, said means including a hydraulic assembly, said assembly being mounted on the frame with a three-point suspension, a portion of the assembly being laterally bent from the longitudinal axis of the assembly, and shock absorbing means engaging said portion for supporting its weight.
2. In combination with an automotive vehicle having a frame, a dumping receptacle

pivotally supported therefrom, means for dumping the receptacle, said means including a hydraulic assembly, said assembly being mounted on the frame with a three-point suspension, a portion of the assembly being laterally bent from the longitudinal axis of the assembly, and shock absorbing means engaging said portion for supporting its weight.

3. In combination with an automotive vehicle having a frame, a dumping receptacle pivotally supported therefrom, means for dumping the receptacle, said means including a hydraulic assembly, said assembly being mounted on the frame with a three-point suspension, the mounting adapted to permit rotary movement of the assembly at one point, a portion of the assembly being laterally bent from the longitudinal axis of the assembly, and shock absorbing means for supporting its weight.

4. In combination with an automotive vehicle including a frame, a body mounted on the vehicle and means for tipping it, said means including a reservoir for fluid depending from said frame and having a portion laterally bent from the longitudinal axis of the vehicle, a pump carried by said reservoir to receive fluid therefrom, a cylinder extending longitudinally of the vehicle, and conduits between the pump and cylinder through which the pump forces fluid to cause tipping of the body.

5. In combination with an automotive vehicle including a frame, a body mounted on the vehicle and means for tipping it, said means including a reservoir for fluid depending from said frame and having a portion laterally bent from the longitudinal axis of the vehicle, a pump carried by said reservoir to receive fluid therefrom, a cylinder extending longitudinally of the vehicle, and conduits formed in the reservoir and communicating with the pump and cylinder.

Signed at Streator, county of LaSalle and State of Illinois, this 8th day of November, 1930.

WILLIAM C. ANTHONY.
LESTER WACHTER.
